UNITED STATES PATENT OFFICE.

PATRICK D. RIORDAN, OF NEW YORK, N. Y.

CLOTHES-DRIER.

1,288,996.

Specification of Letters Patent. Patented Dec. 24, 1918.

Application filed April 29, 1918. Serial No. 231,513.

To all whom it may concern:

Be it known that I, PATRICK D. RIORDAN, a citizen of the United States of America, residing at the borough of Manhattan, in the city, county, and State of New York, have invented certain new and useful Improvements in Clothes-Driers, of which the following is a specification, reference being made to the accompanying drawings.

10 This invention relates to improvements in clothes-driers and particularly to improvements in the clothes-drier patented to me April 2d, 1918, by Letters Patent #1261692. An object of this invention is 15 to provide a clothes-drier in which the wet clothes may be hung upon the drier within the privacy of one's own laundry and free from observation by the neighbors while presenting the inelegant appearance forced 20 upon one who is doing laundry work. Another object of this invention is to provide a clothes-drier in the operation of which there will be no need of leaning out of the window with the attendant danger of losing 25 one's balance and falling therethrough, no need of standing on fire-escapes and no danger of falling therefrom, therefore, due to such necessity. Moreover, by reason of the fact that the housewife doing her own 30 laundry work is, in the use of the clothes-drier hereinafter particularly described, protected from the elements, while engaged in putting out the family wash to dry and in taking the same in when dry, she is safe- 35 guarded from diseases due to exposure to cold and inclement weather. A third object of this invention is to provide a clothes-drier which will be simple in construction, comparatively cheap in manufacture and 40 therefore within the financial reach of the poorer classes, and safe, efficient, handy, convenient and durable in operation and use.

In the drawings illustrating the principle 45 of this invention and the best mode now known to me of applying that principle, Figure 1 is a plan of the clothes-drier, the outside position of the line-bearing drying-frame being indicated by the dotted lines; 50 Fig. 2 is a section on the line 2—2 of Fig. 1; Fig. 3 is a detail illustrating the bracket that supports one side of the carrier-frame; Figs. 4 and 5 are details showing modified forms of the bracket illustrated in Fig. 3; 55 and Figs. 6 and 7 are fragmentary details

illustrating in plan and elevation, respectively, a corner of the drying-frame.

The swinging, supporting frame *a* serves as a carrier and runway for the clothesline-carrying, drying frame *b* and is open at its 60 inner end, its side-rails *a'* being connected at their outer ends by the crossbar *a''*. The inner end of each side-bar *a'* is formed with a hole *a^x*, through which passes the inner free end of a stub-shaft or pivot-pin *c'* that 65 projects inwardly from the bracket *c* fastened to one of the sides of the window-frame *d*. Near the center of the outer cross-bar *a''*, there is fastened (as by the screw-eye *e'*), one end of a rope or cord *e*, which 70 is rove over a pulley *f* fastened to the top of the window-frame *d* and the other end of which is secured to a fastening device *g* mounted on the bottom *d'* of the window-frame *d*. When the drying-frame *b* is 75 mounted upon the carrier-frame *a*, the latter may be swung upwardly on its pivots *c'* by pulling downwardly upon the vertical part of the rope *e* (Fig. 2) and may be lowered into its operative position by pay- 80 ing out the rope *e*. The side-bars *a'* of the carrier-frame *a* are secured on their pivot-pins *c'* by means of the lock-pins *c''* which are attached to the brackets *c* by means of chains *h* and, in their operative positions, 85 pass through the holes *a^x* formed in the inner ends of the pivot-pins *c'*.

The drying-frame *b* is four-sided and rectangular and is provided with several lengths of clothesline *i* that is passed through holes 90 *i'* formed in the cross-bars *b'* and is stretched therebetween so as to be taut. As shown in Figs. 1 and 2, the active lengths of the clothesline *i* run parallel to the side-bars *b''* of the drying-frame *b*. On each end of 95 each cross-bar *b'*, there is mounted a strap or plate *j* formed with a guide-eye *j'* at its outer end (Figs. 6 and 7). As is clearly shown in Fig. 1, the guide-straps *j* extend parallel to and lengthwise of the crossbar *b'* to which they are fastened, and the guide-eyes *j'* project laterally from the frame *b*. When the two frames *a*, *b*, are in assembled relation to each other (Fig. 1), the side-rails *a'* of the carrier-frame *a* pass through 100 the guide-eyes *j'* that project from the ends of the outer cross-bar *b'* of the drying-frame *b*, whereby the latter is arranged to slide back and forth on the carrier-frame *a*. When the drying-frame *b* is pushed out- 110

wardly along the carrier-frame *a* to the position indicated by the dotted lines in Fig. 1, the guide-eyes *j'* that project laterally from the ends of the inner crossbar *b'* of the drying-frame *b*, engage the inner ends of the side-rails *a'* of the carrier-frame *a*; and the drying-frame may be locked in its outermost position by passing lock-pins *b''* through holes *a''* formed in the inner ends of the side-rails *a'*.

Mounted centrally on the inner crossbar *b'* of the drying-frame *b* (Figs. 1 and 2), there is a prop-holder *k* the jaws *k'* of which engage the inner cross-bar *b'* and are held clamped thereto by means of the screw *k''* (Fig. 2). The holder *k* is formed, at the middle of its outer edge-portion, with a hole *k''*, through which a prop *m* is passed (Fig. 2) and in which the same is held, in its adjusted position, by means of the thumb-screw *m'*. As is obvious, the prop *m* is used to support the inner end of the drying-frame *b*, when the latter is drawn inwardly to receive the wet clothes; and, when the drying-frame *b* is to be pushed outwardly along the carrier-frame *a*, the screw *m'* is loosened and the prop *m* is removed. As is clearly shown in Fig. 2, the brackets *c* are fastened to the window-frame *d* at a height which will permit the laundress to hang the wet clothes with ease upon the drying-frame *b* and which will insure, nevertheless, that the clothes, in passing over the window-sill *d'*, will not come in contact therewith. In Fig. 4, there is illustrated a modified form of bracket in which the pivot-pin *c'* may be adjusted vertically. Here a screw *n* having a hollow, tubular head *n'* is screwed into the side of the window-frame *d*. One end of the pivot-pin *c'* is substantially integral with a sleeve *o*, which is slipped over the upper end of a bracket-rod *p*, whereby the sleeve *o* is slidably mounted thereon. The upper end of the bracket-rod *p* is then passed through the tubular head *n'* of the screw *n* and its lower end is fastened, as by the lag-screws *p'*, to the side of the window-frame *d*. The bracket-rod *p* is formed with a series of holes *p''* throughout nearly all its length; and the pivot-pin *c'* is maintained at its adjusted height by passing a lock-pin *o'* through the hole *o''* formed in the sleeve *o*, and one of the holes *p''*. In order to permit the sleeve *o* to be slipped freely along the perforated portion of the bar *p*, this portion of the latter is offset from the window-frame *d* by forming a bend or shoulder in the bracket-rod *p*, as at *p''* (Fig. 4).

To provide for those cases in which the width of the window varies, the bracket *c''* (Fig. 5) has been devised by me. From the top of the bracket *c''*, there project upwardly the posts *q* the upper ends of which are formed with guide-eyes *q''*, through

which is slipped a perforated bar *r* one end of which is formed with an eye *r'*. The inner end of the side-rail *a'* is passed therethrough and is locked therein by means of the lock-pin *r''* attached, by means of a chain *r''*, to the bracket *c''*. As will be readily understood from an inspection of Fig. 5, the perforated bar *r* may be slipped lengthwise of itself and laterally of the window-frame *d* and may be secured, in its adjusted position, by passing lock-pins *r''* through perforations lying outside of the guide-eyes *q''*.

The structure illustrated in Fig. 1 is assembled in the following manner: The side-rails *a'* of the carrier-frame *a* are passed through the guide-eyes *j'* that project from the outer cross-bar *b'* of the drying-frame *b*, which is then slipped along the carrier-frame. One side-rail *a'* is engaged with its pivot-pin *c'* by passing the latter through the hole *a''* formed in the side-rail, and then the other pivot-pin *c'* may be engaged with the other side-rail *a'*, which, being somewhat flexible, may be bent inwardly toward its co-acting side-rail *a'* to permit this engagement of the pivot-pin and side-rail, after which the lock-pins *c''* are put in the holes *a''*. The rope *e* is rove through the guide-pulley *f* and its free end is fastened as at *g*, Fig. 2, the carrier-frame *a* being in the horizontal position shown. The drying-frame *b* is drawn inwardly, the outer pair of guide-eyes *j'* sliding along the side-rails *a'*; and, after the drying-frame *b* is withdrawn within the house, the prop-holder *k* is mounted upon the inner cross-bar *b'* and is secured thereto by tightening the clamp-screw *k''* and thereby closing the jaws *k'* toward each other. The prop *m* is fitted in the hole *k''* and, after it has been suitably adjusted therein, it is fastened in place by tightening the thumb-screw *m'*. The apparatus is now ready for use; and the laundress proceeds to hang the washed clothes on the lines *i*. After the clothes, still wet, are hung thereon, she grasps the inner crossbar *b'* so as to support the drying-frame *b*, loosens the screw *m'*, removes the prop *m* and pushes the drying-frame *b* along the carrier-frame *a* and outwardly, until the guide-eyes *j'* projecting laterally from the inner crossbar *b'* engage the inner ends of the side rails *a'*, whereupon the lock-pins *b''* are passed through the holes *a''*, thereby locking the drying-frame *b* in place. The lower window-sash (not shown) may be now closed and the clothes left exposed to the sunlight and air to dry. After the clothes are dried, the window is opened, the lock-pins *b''* are removed, the drying-frame *b* is drawn inwardly and the prop *m* fastened in place, whereupon the dry clothes may be removed from the clothes-lines *i*. The prop *m* is now removed, the

drying-frame *b* is pushed outwardly along and over the carrier-frame *a*, the lock-pins *b**, are put in place in the holes *a** in the inner ends of the side-rails *a'* and the two frames *a*, *b*, are swung into a substantially upright position about and upon the pivot-pins *c*', by hauling downwardly upon the rope *e*, which is then made fast to the fastening device *g*.

10 In case of inclement or rainy weather, the drying-frame *b* may be removed from its carrier-frame *a* and suspended, as by means of its guide-eyes *j*', within the house, wherein the clothes may be dried.

15 In accordance with the patent statutes, I have herein described and shown the preferred embodiment of this invention and have explained the principle thereof; but I recognize that departures may be made 20 from the forms of execution herein disclosed without varying from the spirit of this invention. Thus, as is shown in Figs. 6 and 7, instead of roving the clothesline *i* through holes *i*'' formed in the cross-bars *b*', eye-bolts *i** may be fastened therein and the lengths of clothesline fastened to the eye-bolts *i**. Such changes are deemed by me to fall within the scope of this invention. The side-bars *a'* of the carrier-frame

25 *a* may be moved toward or from each other along the cross-bar *a***, so as to adjust the width of the frame *a* to the width of the window *d*; and the side-bars *b*'' of the dry-

ing-frame *b* may be similarly adjusted along the cross-bars *b*' to adapt the drying-frame 35 to the width of the window. Of course, the straps *j* will be properly placed on the cross-bars *b*' so that the side-bars *a'* will pass through the eyes *j*'. The side-bars *b*'' may be replaced by a single bar connecting 40 the mid-portions of the cross-bars *b*'.

I claim:

A clothes-drier including a carrier-frame hingedly mounted in an opening formed in the wall of the house and arranged to be 45 swung up and down toward and from said wall, said carrier-frame having side-bars that project inwardly beyond their pivotal points; and a clothesline-carrying drying-frame mounted on said carrier-frame and 50 arranged to be withdrawn within and moved out of the house through the opening in the wall thereof; said drying-frame being provided with means for interlocking with the inwardly-projecting parts of the 55 side-bars of the carrier-frame, when the clothes-drier is to be swung up against the building out of use.

Signed at the borough of Manhattan, city, county and State of New York, this 27th 60 day of April, A. D. 1918, in the presence of the two undersigned witnesses.

PATRICK D. RIORDAN.

Witnesses:

JAMES HAMILTON,
LILLIE VREELAND.
